UNITED STATES PATENT OFFICE.

DAVID C. CAMP, OF MILLEDGEVILLE, GEORGIA, ASSIGNOR OF ONE-HALF
TO M. F. BROWN, OF KANSAS CITY, MISSOURI.

DESIGN FOR A CREAM-SEPARATOR.

SPECIFICATION forming part of Design No. 31,254, dated July 18, 1899.

Application filed June 13, 1899. Serial No. 720,412. Term of patent 14 years.

To all whom it may concern:

Be it known that I, DAVID C. CAMP, a citizen of the United States, residing at Milledgeville, in the county of Baldwin and State of Georgia, have invented a certain new and useful Design for a Cream-Separator; and I do declare the following to be a full, clear, and exact description of the invention, such as will enable others skilled in the art to which it applies to make and use the same.

My invention relates to a design for a cream-separator; and the novelty consists in the design or configuration of the cream-separator as illustrated in the accompanying drawing, in which the figure is a perspective view of the cream-separator, illustrating my design.

The essential feature of my design is a cylindrical body 1, having a conical top 2, on the apex of which appears a short cylindrical tube 3, and on each side is a strap-handle 4. A vertical rectangular scale-panel 5 appears on the front of the cylindrical body 1, and below this scale is a duplex or double faucet 6, terminating in a common discharge-pipe 7. A threaded horizontal nipple 8 appears on

the side of the cylindrical body 1 a short distance above the bottom, and between this externally-threaded nipple and the bottom is a smaller threadless nipple 9. Suitable drop-handles are fixed to the body portion, one of which is shown at 10. A vertical tapering tube 12, terminating at its upper end in a funnel-shaped mouth 13, appears on the outside of the body, and it is fixed at its lower end by a short connection 14 to the body near its bottom. A concentric band or flange 15 surrounds the lower end of the bottom.

Having thus fully described my invention, what I claim as new and useful, and desire to secure by Letters Patent of the United States, is—

The design for a cream-separator, substantially as herein shown and described.

In testimony whereof I have hereunto set my hand in presence of two subscribing witnesses.

DAVID C. CAMP.
